LOUIS JOHN HERTLIN, OF BROOKLYN, NEW YORK.

PROCESS FOR PRODUCING PRINTING-PLATES.

1,276,697.

Specification of Letters Patent. Patented Aug. 20, 1918.

Application filed November 20, 1915. Serial No. 62,579.

To all whom it may concern:

Be it known that I, LOUIS J. HERTLIN, a citizen of the United States, and a resident of New York, in the county of Kings, borough of Brooklyn, and State of New York, have invented a new and useful Process for Producing Printing-Plates, of which the following is a specification.

My process relates to the production of printing plates used for printing different colors, and the object is to devise a method whereby such plates may be produced without the need of skilled labor and at comparatively little cost. The process is particularly suitable for printing exact reproductions of designs of linoleums, oil-cloth, and the like.

My process while photo-lithographic does not require a camera, a master or key sheet of transparent material being provided upon which the outlines or border lines of the design are formed, as by printing in a press or otherwise; this sheet being used in the manner of a photographic negative for making prints on special plates such as zinc or aluminum or on stone. In my process the master sheet is altered for each plate after the photographic print has been made. The treatment of the plate is as usual.

In the appended drawing forming a part of this specification, in which like reference characters refer to like parts in each of the views,

Figure 1 represents the master transparent sheet which is employed in the formation of all the color plates.

Fig. 1^A is a positive photographic print made from the master sheet upon a transparent sheet.

Fig. 1^B is a view of the border line plate.

Fig. 2 is a reversed view of the master sheet with certain spaces blocked out to form one color plate.

Fig. 2^A is a view of the color plate made by means of the master sheet as blocked out in Fig. 2.

Fig. 3 is a reversed view of the master sheet with certain spaces blocked out to form another color plate.

Fig. 3^A is a view of the color plate made by means of the master sheet as blocked out in Fig. 3.

Fig. 4 is a reversed view of the master sheet with certain spaces blocked out for another color plate.

Fig. 4^A is a view of the color plate made

by means of the master sheet as blocked out in Fig. 4.

Referring to the drawings, 5 is a sheet of transparent material such as celluloid on which is printed or otherwise provided a straight line design as common in designs of linoleum and oil-cloth. As shown in Fig. 1, the lines 6 forming the design run diagonally on the sheet. These lines as soon as impressed upon the sheet are covered with an opaque powder, preferably of a readily distinguishable color, as for example bronze powder. This renders the lines of ink impenetrable to light.

After the powdered ink has dried, the similar spaces defined by the lines 6 are colored identically for identification purposes, and as shown, the central space R is colored red. The triangular spaces B dominating the right angles of the square are colored blue and the spaces Y dominating the sides of the square are colored yellow. All these colors are transparent, and in view of the fact that the lines 6 are of sufficient width, the colors may be applied by unskilled labor, as no care is required, the lines 6 presenting sufficient margin for that purpose.

To obtain the desired negative from this plate, the same is turned face down and some opaque in the form of paint, preferably such as water colors, is applied to the transparent spaces which are to be made impenetrable to light. As shown in Fig. 2, the transparent sheet 5 has been blocked out with opaque paint in the spaces B and Y, in other words, leaving only the square R transparent to light. Again, in view of the width of the lines 6, the application of the opaque paint can be readily done by unskilled labor.

When a zinc or aluminum plate which has been coated with a substance sensitive to light is exposed through the sheet 5, as shown in Fig. 2, and then etched, a plate 8 such as shown in Fig. 2^A will result. The embossed part of the plate will be R¹. This plate will be the red printing plate.

The opaque paint is then washed off from the sheet 5 and the same is again coated with paint so as to render the spaces R and Y impenetrable to light and leaving the spaces B transparent to light, (see Fig. 3 indicating the sheet 5 when so coated). When a zinc or aluminum plate coated with a light sensitive substance is exposed to light through the sheet 5 as shown in Fig. 3 and etched, a plate 10 will result (see Fig. 3^A) which has

an embossed surface B^1 to form the blue printing plate. If the paint is again washed off from the bottom surface of the sheet 5 and the same coated with opaque paint to render the spaces R and B impenetrable to light and leaving the spaces Y penetrable to light (see Fig. 4) and then a zinc or aluminum plate is sensitized and exposed to light through said sheet shown 10 in Fig. 4, a printing plate 12 (see Fig. 4^A) will result which has raised surfaces Y^1 which is to form the yellow printing plate. When a sheet of paper has been printed on by the three plates 8, 10 and 12, the colors 15 are in the respective spaces as indicated in Fig. 1, but the lines 6 are not produced thereon. The surfaces corresponding to these lines are unprinted by reason of the fact that the printing surfaces R^1 , B^1 and 20 Y^1 do not touch each other, and it is necessary to make another printing plate for these lines.

In Fig. 1^A is shown a supplementary sheet of transparent material 13 previously sensitized and exposed through the sheet 5 in its 25 normal condition. The resulting positive presents the line 6 clear and the color spaces opaque; and when the plate 14 previously sensitized has been exposed through the sheet 13 the unetched lines 6^A form the printing surface of said printing plate, and by means of which any distinctive color may be printed upon the paper already having the three-color impression thereon.

Because the colors may be applied by unskilled labor and because of the fact that 35 since the opaque is applied upon the reverse of the transparent master sheet, the latter may be used repeatedly without destroying the design on the face thereof a simple and economical process is produced.

Having fully described my process, what I claim as new and desire to secure by Letters Patent is:

1. The process for producing printing 45 plates which consists in impressing a design with ink upon the face of a transparent sheet, dusting upon the ink a powder adapted to render the part covered by ink impenetrable to light, then blocking out those parts 50 of the sheet which are to be rendered impenetrable to light by means of a washable opaque paint by applying the same to the back of the sheet, and using the so prepared sheet as a negative for producing a 55 printing plate.

2. The process for producing printing plates which consists in impressing with ink a design upon the face of a transparent sheet, the lines of the design being of substantial width, covering the ink of the design with a powder which renders the ink covered part of the transparent sheet impenetrable to light, applying a washable opaque substance to the back of the sheet in 65 the desired spaces outlined by the design, then producing a printing plate from the so formed negative, then removing the opaque substance from the back face of said sheet, and applying a similarly washable opaque 70 substance to the back in different spaces within the spaces outlined by the design and producing a printing plate from the so formed negative.

In testimony whereof I have signed my 75 name to this specification in the presence of two subscribing witnesses.

LOUIS JOHN HERTLIN.
